UNITED STATES PATENT OFFICE.

STEPHEN G. ROGERS, OF PARKERSBURG, WEST VIRGINIA, ASSIGNOR OF ONE-HALF TO
ROBERT E. BILLS, OF PARKERSBURG, WEST VIRGINIA.

HORSESHOE.

1,245,032.

Specification of Letters Patent. Patented Oct. 30, 1917.

Application filed February 9, 1917. Serial No. 147,628.

To all whom it may concern:

Be it known that I, STEPHEN G. ROGERS, a citizen of the United States, residing at Parkersburg, in the county of Wood and 5 State of West Virginia, have invented certain new and useful Improvements in Horseshoes; and I do hereby declare the following to be a full, clear, and exact description of the invention, such as will enable others 10 skilled in the art to which it appertains to make and use the same.

This invention relates to a horseshoe and has for one of its objects the provision of a device of this character having means for 15 forming a cushioned shoe which will aid in curing draft animals of sore or infected feet.

Another object of this invention is to provide the shoe with each end bifurcated to receive a wedge shaped rubber for forming 20 cushioned heels to the shoe.

A further object of this invention is to provide detachable heel calks for each end of the shoe which will aid in preventing displacement of the cushioning means.

25 A further object of this invention is to provide novel means of detachably securing the calks to the shoe.

A still further object of this invention is the provision of a horseshoe of the above 30 stated character, which shall be simple, durable, and efficient, and which may be manufactured and sold at a comparatively low cost.

With these and other objects in view as 35 will become more apparent as the description proceeds, the invention consists of certain novel features of construction, combination and arrangement of parts as will be hereinafter more fully described and claimed.

40 For a complete understanding of my invention, reference will be had to the following description and accompanying drawing, in which:—

Figure 1 is a bottom plan view of a horse- 45 shoe, constructed in accordance with my invention;

Fig. 2 is a detail sectional view taken on the line 2—2 of Fig. 1, illustrating the cushioning means;

50 Fig. 3 is a perspective view of the wedge shaped rubber for forming the cushions to the heels;

Fig. 4 is a detail sectional view taken on the line 4—4 of Fig. 1;

Fig. 5 is a perspective view of one of the 55 calks; and

Fig. 6 is a fragmentary bottom plan view illustrating the formation of the slots.

Referring in detail to the drawing, the numeral 1 indicates a horseshoe having a toe portion 2 and the heel portions 3. The shoe 1 is provided with usual nail openings 4 for securing the shoe to the draft animal's hoof by nails being driven through the openings and into the hoof. The toe portion of the 65 shoe 1 is provided with a dove-tailed groove 5 to receive the dove-tailed portion of a calk 6 which has the beveled spaces 7 providing a toe calk which can be readily removed from the shoe whenever desired. Formed 70 upon the toe portion 2 is the usual upstanding toe clip 8 for engagement with the animal's hoof.

The heel portions 3 of the shoe 1 are each bifurcated to receive a wedge shaped member 9 constructed from rubber or other resilient material. The reduced end of the wedge 9 extends sufficiently far enough to prevent one of the nails which secure the shoe 1 to an animal's hoof to pass through 80 for retaining the wedge shaped member 9 within the bifurcated portion of the heels 3. The upper faces of the heel portions are provided with apertures to receive pins 10 which are driven into the wedges 9 for aiding in preventing said wedges from being displaced in the bifurcated ends of the heel portions 3. The lower or bottom spaces of the heel portions 3 are provided with key-hole slots 11 to receive heel calks 12 which 90 will be hereinafter more fully described. The wedges 9 are provided with elongated recesses for sockets 13 which register with the key-hole slots 11, for receiving the inner ends of the heel calks 12. 95

The heel calks each consist of a shank 14 having oppositely disposed flattened surfaces 15 and have formed upon one of the ends disk 16 of circular formation while at the opposite end is formed a pointed head 17. 100 In applying the heel calks 12, they are inserted within the circular openings of the key-hole slots 11 and the flattened faces 15 of the shanks 14 permit the heel calks to be slid in the direction of the ends of the heels 105 or smaller end of the key-hole slots having the flanges 16 within the recesses 13 of the wedge shaped members 9 and by giving the

heel calks one-half turn, the flattened faces will prevent the calk from accidentally moving within the heel slots 11.

From the foregoing description taken in connection with the accompanying drawings, it will be noted that the heel calks are so applied to the shoe 1 that they may be readily removed whenever desired and also when applied to the shoe will aid in holding the 10 wedge shaped members 9 from displacement within the bifurcated ends or heel portions of the shoe. It will also be noted that the toe calk 6 may be readily removed when desired, along with the heel calks 12 providing 15 a smooth shoe. When calks have been removed from the shoe, the wedge shaped members 9 are retained within the bifurcated ends of the heel portions 3 by the pins 10 and the nails which secure the shoe to the 20 animal's hoof. By placing the wedge shaped members within the heel and being constructed of rubber or other resilient material forms a cushioned heel to the shoe which will aid in curing raw or infected feet of draft 25 animals.

While I have shown and described the preferred embodiment of my invention, it will be understood that minor changes in construction, combination and arrangement of 30 parts may be made without departing from the spirit and scope of the invention as claimed.

Copies of this patent may be obtained for five cents each, by addressing the "Commissioner of Patents, Washington, D. C."

Having thus described my invention, what I claim is:—

1. A horseshoe comprising a body including toe and heel portions, said heel portions being bifurcated, a resilient wedge secured within the bifurcation of the heel portion and having recesses, said heel portions having heel slots, shanks extending into the heel slots, flanges formed on said shanks and received within the recesses of the wedges, and pointed heads formed upon the shanks to form heel calks.

2. A horseshoe comprising a body including toe and heel portions, said heel portions being bifurcated, resilient wedge shaped members within the bifurcations, pins extending through the heel portions and into the wedge shaped members, said wedge shaped members having recesses, said heel portions having key-hole slots, calks extending through the key-hole slots and into the recess of the wedge shaped members to hold them against accidental movement and means on the calks for retaining them in the recesses of the members.

In testimony whereof I affix my signature in presence of two witnesses.

STEPHEN G. ROGERS.
